[57] CLAIM

The ornamental design for a wheel cover for chain block, as shown and described.

DESCRIPTION

FIG. 1 is a perspective view of a wheel cover for chain block showing our new design;

FIG. 2 is a front view thereof;

FIG. 3 is a rear view thereof;

FIG. 4 is a left side view thereof;

FIG. 5 is a top plan view thereof;

FIG. 6 is a bottom plan view thereof; and,

FIG. 7 is a reference perspective view of a chain block showing a state in which the wheel cover is stored.

A right side view of the wheel cover for chain block is symmetrical to the FIG. 4. The items depicted by broken lines in FIG. 7 represent an environment within which the claimed invention is used, and form no part of the claimed design.
